UNITED STATES PATENT OFFICE.

ROBERT R. SMITH, OF BROOKLYN, NEW YORK.

CORNER FASTENING FOR BEDSTEADS.

Application filed February 2, 1920. Serial No 355,879.

To all whom it may concern:

Be it known that I, ROBERT R. SMITH, a citizen of the United States, and a resident of Brooklyn, in the county of Kings and State of New York, have invented certain new and useful Improvements in Corner Fastenings for Bedsteads, of which the following is a specification.

The invention relates to improvements in beds and more particularly to improvements in what are commonly designated as three-piece beds, these comprising a head-frame, a foot-frame and a mattress or spring carrying frame intended for detachable connection with the head and foot frames. My invention has reference more particularly to the corner-fastenings by which the mattress or spring carrying frame may be conveniently and rigidly secured to the head and foot frames, and resides more especially in novel corner-fastening members secured to the side-rails of the spring or mattress carrying frame and which usually receive the end-rails of said frame, and novel locking members connected with the corner posts of the bedstead and adapted to receive and interlock with said corner fastening members of the spring or mattress frame, the whole being so arranged, combined and constructed that a very substantial bedstead frame may be produced.

The invention resides in the novel features and construction of interengaging parts hereinafter described, and particularly pointed out in the claims, and said invention will be fully understood from the detailed description hereinafter presented, reference being had to the accompanying drawings, in which:

Fig. 1 is a side elevation, partly broken away, of one corner-portion of a bedstead equipped with the corner-fastening of my invention;

Fig. 2 is a top view, partly in section and partly broken away, of the same;

Fig. 3 is a horizontal section through the same, taken on the dotted line 3—3 of Fig. 1;

Fig. 4 is an outer end elevation of the corner-fastening member secured to the side rail of the spring or mattress carrying frame, and

Fig. 5 is a side elevation of a corner portion of a bedstead employing my invention in a form varying from the embodiment thereof shown in Figs. 1 to 4 inclusive and therefor constituting a modified construc-

tion, which, however, may in some instances be regarded as the preferred form of the invention.

In the drawings, 10 designates a portion of a corner-post of a metal bedstead, 11 a portion of one of the side rails thereof, 12 a portion of one of the angle-iron end rails, 13 the usual helicals connected with said end rail, and 14 a portion of the mattress or spring supported by said helicals from the end rail 12.

My invention has reference more particularly to means, commonly called a corner-fastening, for connecting the side-rails 11 and end-rails 12 with the corner-posts of the bedstead.

Referring to Figs. 1 to 4 inclusive, one member of the corner-fastening is numbered 15 and the other member thereof 16, the member 15 being secured to the side rail 11 and the member 16 to the corner-post 10. The members 15, 16 are, preferably, each an integral metal casting.

The fastening member 15 has a vertical outer end face-plate 17, a top flange 18, a lower partly tubular portion 19 to engage and be secured to the side-rail, an inner vertical strengthening web 20, and an outwardly projecting vertical web 21, which is in horizontal alignment with the web 20 and projects toward the corner post 10.

The tubular portion 19 of the member 15 forms a socket for the end of the side-rail 11 and may be secured thereto by a rivet 22. The upper portion of the face-plate 17 and the flange 18 may conveniently have the end 23 secured thereto by means of rivets 23.

The essential feature of the member 15 pertains to the web 21, which is a locking bar and has on its opposite sides substantially vertical integral corresponding ribs 24 and on its upper and lower outer end edges abutment projections 25, 26, whose operative faces are vertical and preferably on the same vertical plane. The web or bar 21 is recessed inwardly between the projections 25, 26 and to the outer vertical edge of the ribs 24, as shown in Figs. 1 and 4. The ribs 24 present at their inner vertical edges substantially flat corresponding downwardly and outwardly inclined wedge-faces 27, at whose lower ends the ribs 24 curve outwardly, as at 28, to facilitate the application of the fastening member 15 to the fastening member 16. The locking bar or web 21 thus provides on its opposite sides the corresponding

wedges 27 and on its outer end the upper and lower abutments 25, 26, these abutments being for cooperation with the fastening member 16, as hereinafter explained.

- 5 The fastening member 16 is preferably in one integral piece and may be conveniently secured to the corner-post 10 by rivets 29, and said member 16 has at its upper and lower end portions, upper and lower abutment faces 30, 31, respectively, and at its opposite sides, corresponding arms 32, which project horizontally toward the member 15 and have on the facing sides of their outer ends corresponding lugs 33, presenting 15 curved inner edges, as indicated by dotted lines in Fig. 1, to the flat wedge faces 27 of the ribs 24. The abutment faces 30, 31 are preferably vertical and in line with each other and they cooperate with the upper and 20 lower abutment faces 25, 26 of the fastening member 15.

In applying the member 15 to the member 16, the said parts are brought together and the outer portion of the locking bar 21 of 25 the member 15 is caused to pass downwardly between the arms 32 of the member 16 with its wedge surfaces 27 against the curved surfaces of the lugs 33 until the abutments 25, 26 on said bar 21 enter into firm engagement with the abutments 30, 31 of the member 16 and become bound thereto by the wedging action of the surfaces 27 against said lugs 33.

The ribs 24 strengthen the bar 21 and the 35 wedges 27 afforded by said ribs have substantially only a point contact with the lugs 33 and therefore are effective in binding the fastening members 15, 16 together. By reason of the provision of two corresponding 40 wedges 27 to engage lugs disposed at opposite sides of the bar 21, the members 15, 16 become very efficiently secured together without liability of one member being in tiltable or rockable relation to the other member. 45 The abutting faces 25, 26 and 30, 31 are of adequate but limited surface area and hence may be conveniently machined or smoothed, if desired, at small expense. The fastening members 15, 16 have, as a whole, been designed with the view of rendering them 50 highly efficient, ready of manufacture and assembly and of great durability.

The face-plate 17 on the member 15 preferably extends laterally beyond both sides of 55 the web or bar 21 and web 20, so as to adapt the member 15 for any post of the bedstead, thus avoiding the necessity of providing right and left hand members 15 for the opposite corner posts of a bedstead. The face-plate 17, may, however, extend laterally beyond only one side of the web 20 and bar 21 should it appear not to be objectionable to make the members 15 as "rights" and "lefts".

In the construction shown in Fig. 5, 40 60 65 66 designates the corner-posts, 41 a side rail of

the mattress or fabric carrying frame, 42 the corner-fastening member secured thereto and 43 the corner-fastening member secured to the post 40. The member 43 has abutment projections 44, 45, side arms 46 70 and rounded lugs 47 corresponding with the like features numbered 30, 31, 32 and 33 respectively in Figs. 1, 2 and 3 and requiring therefore no special description except to point out that the arms 46 are lower on the member 43 than the arms 32 on the member 16. The member 42 has a socket 48 to receive the end of the side rail 41 and a body or vertical bar portion 49 on whose upper and lower ends are formed abutment projections 50, 51 respectively and on whose opposite side faces are formed substantially vertical ribs 52 which are oppositely inclined on the inner edges of their upper and lower portions to afford upper and lower wedges 53, 80 85 54 for respective engagement with the curved surfaces of the lugs 47. The abutment projections 50, 51 correspond with the like features numbered 25, 26 in Figs. 1, 2 and 4 and they cooperate with the abutment projections 44, 45 on the member 43 in a manner which will be understood from the description hereinbefore given with respect to the abutments 25, 26 and 30, 31. It is intended that the member 42 may be 90 applied to any corner of the mattress-frame and that no care need be taken as to which end of said member may be at the top and hence each horizontal half of said member 42 is a duplicate of the other half thereof, 100 one half having the wedges 53 and the other half the wedges 54 and either pair of wedges being adapted to be passed downwardly between the arms 46 to engage the lugs 47. The member 42 of the construction described 105 presents some advantages in lessening the care which ordinarily would be required in assembling the parts of a bedstead but said member when in position performs the same duties as the aforesaid member 15 and in the same way. It is my invention to apply my corner-fastening members 15, 42 to box-spring mattresses, as well as to the frames of spring fabric mattresses, and the members 42 will be found to be very convenient of application to corner portions of box-spring mattresses having suitable frames to receive them.

What I claim as my invention and desire to secure by Letters-Patent, is:

1. In a bedstead, a corner-post and a main frame, in combination, corner-fastening members therefor and respectively secured thereto, the member secured to the main frame having a body part, a vertical face-plate thereon and a central vertical plate web projecting outwardly from said face-plate and formed on its opposite exposed side faces and at the outer vertical edge thereof with vertically extending and out- 130

wardly laterally projecting corresponding ribs whose lower inner edge surfaces incline downwardly and outwardly and constitute wedges and which plate web has its upper 5 and lower ends projecting outwardly beyond said ribs to form upper and lower abutment edges located above and below said wedges and on a vertical plane outwardly from and centrally between the vertical 10 planes of said ribs, said abutment edges being spaced from and independent of each other and leaving said side ribs freely exposed, and the member secured to the corner-post having a pair of spaced apart project- 15 ing parallel arms between which said web may be passed and which arms have on their outer ends inwardly projecting facing lugs adapted to receive behind them and enter into binding engagement with said rib 20 wedges, and suitable abutment surfaces being present to receive said upper and lower projecting abutments on the web of the frame member.

2. In a bedstead, a corner-post and a main 25 frame, in combination, corner-fastening members therefor and respectively secured thereto, the member secured to the main frame having a body part, a vertical face-plate thereon and a central vertical web 30 projecting outwardly from said face-plate and formed on its opposite exposed side faces and at the outer vertical edge thereof with vertically extending and outwardly laterally projecting corresponding 35 ribs whose lower inner edge surfaces incline downwardly and outwardly and constitute wedges and which plate web has its upper and lower ends projecting outwardly beyond said ribs to form upper and lower 40 abutment edges located above and below said wedges and on a vertical plane outwardly from and centrally between the vertical planes of said ribs, said abutment edges being spaced from and independent of each 45 other and leaving said ribs freely exposed, and the member secured to the corner-post having a body part, upper and lower independent vertical abutments projecting from the upper and lower ends of said body part 50 and to be engaged with the said abutments on the web of the frame member and a pair of spaced-apart parallel arms spaced from and projecting intermediate and beyond the vertical plane of said vertical abutments and between which arms said web may be passed 55 and which arms have on their outer ends inwardly projecting facing lugs adapted to receive behind them and enter into binding engagement with said rib wedges.

3. In a bedstead, a corner-post and a main 60 frame, in combination, corner-fastening members therefor and respectively secured thereto, the member secured to the main frame having a body part, a vertical face-plate thereon and a central vertical web 65 projecting outwardly from said face-plate and formed on the opposite exposed side faces and at the outer vertical edge thereof with vertically extending and outwardly laterally projecting corresponding 70 ribs whose lower inner edge surfaces incline downwardly and outwardly and constitute wedges and which plate web has its upper and lower ends projecting outwardly beyond said ribs to form upper and lower 75 abutment edges located above and below said wedges and on a vertical plane outwardly from and centrally between the vertical planes of said ribs, said abutment edges being spaced from and independent of each 80 other and leaving said ribs freely exposed, and the member secured to the corner-post having a body part, upper and lower independent vertical abutments projecting from the upper and lower ends of said body part 85 and to be engaged with the said abutments on the web of the frame member and a pair of spaced-apart parallel arms spaced from and projecting intermediate and beyond the vertical plane of said vertical abutments and between which arms said web may be passed 90 and which arms have on their outer ends inwardly projecting facing lugs having convex lateral surfaces adapted to receive and enter into binding engagement with said 95 rib-wedges, and said rib wedges where they engage said lugs having flat lateral faces.

Signed at New York city, in the county of New York and State of New York, this 30th day of January A. D. 1920.

ROBERT R. SMITH.
